FOREIGN PATENT DOCUMENTS

CN 305973130 * 12/2018
CN 305973131 * 12/2018*Primary Examiner* — Paula Allen Greene(57) **CLAIM**

The ornamental design for earbud, substantially as shown and described.

DESCRIPTION

FIG. 1 is a front perspective view of an earbud showing our new design for the right ear, the earbud for the left ear is a mirror image;

FIG. 2 is a rear perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.

The dotted line portions of the drawings represent environmental structure only and do not form part of the claimed design.

1 Claim, 3 Drawing Sheets(56)
